A technical line drawing of a mechanical assembly. It features a central vertical post with a ribbed cylindrical section. A horizontal plate is attached to the top of the post. On the left side of the plate, there is a rectangular cutout with a circular hole in its center. A curved bracket, labeled 26, is attached to the bottom of the post. A small circular component, labeled 27, is positioned at the bottom right. To the right of the post, there is a vertical structure with a circular opening, labeled 28. A small figure, labeled 29, is shown standing next to this structure. The entire assembly is set against a background with horizontal lines and a grid pattern.

UNITED STATES PATENT OFFICE.

JOHN AXEL KINDBERG, OF GAITHER, OKLAHOMA.

WARDROBE.

1,072,473.

Specification of Letters Patent.

Patented Sept. 9, 1913.

Application filed October 22, 1912. Serial No. 727,233.

To all whom it may concern:

Be it known that I, JOHN AXEL KINDBERG, a citizen of the United States of America, residing at Gaither, in the county of Okmulgee and State of Oklahoma, have invented 5 certain new and useful Improvements in Wardrobes, of which the following is a specification, reference being had therein to the accompanying drawing.

10 This invention relates to wardrobes of the portable type and the principal object of the invention is to provide a wardrobe which will be light in construction and which can be easily taken to pieces and set up again, 15 thus permitting the wardrobe to be very easily conveyed from one place to another.

Another object of the invention is to so construct the wardrobe that when in a set up position it will be very rigid and not 20 liable to easily come apart.

Another object of the invention is to provide the wardrobe with an improved shelf which is so constructed that it will be removably supported between the side walls 25 of the wardrobe.

Another object of the invention is to provide an improved type of cover for the wardrobe which is placed above the shelf and which carries an improved means for 30 movably securing the curtains.

In the accompanying drawings:—Figure 1 is a front elevation of the wardrobe the curtains partially spread apart. Fig. 2 is a section along the line 2—2, of Fig. 3. Fig. 35 3 is a section along the line 3—3, of Fig. 2. Fig. 4 is a section along the line 4—4, of Fig. 3. Fig. 5 is a perspective view of the cover looking at the inner face. Fig. 6 is an enlarged sectional view showing the manner 40 of supporting the shelf and holding the same in place. Fig. 7 is a perspective view of the upper edge of one of the curtains with the devices for supporting the curtains.

Referring to the accompanying drawings 45 it will be seen that this invention comprises the side walls which are connected together by braces and which support the shelf and cover. Each of these side walls comprises the vertical side bars 10 and 11 which are 50 formed from angle iron. These side bars are connected by means of the diagonal braces 12 and by the upper and lower cross bars 13 and 14. Cross bars 15 are also provided at the upper portion of the side walls 55 and overlap the bracing bars 14 as clearly shown in Fig. 2 so that supporting ledges

will be formed by the upper edges of the cross bars 14 and the inner faces of the cross bars 15. A key 16 is secured in the upper portion of each of the angle bars with its 60 lower end resting upon the cross bar 14. The lower ends of the angle bars are secured to the feet 17 which are tapered and terminate in blunt ends. These feet are relatively heavy and thus prevent any 65 danger of the wardrobe toppling over.

It is of course obvious that if desired the portions of this wardrobe may be formed from wood or any suitable composition molded into the desired forms, but it is preferred to have the device made from metal 70 so that while the portions of the device will be comparatively light the wardrobe will be very strong in construction.

When assembling this wardrobe the side 75 walls are first set up as shown in Fig. 2 and are then connected by the diagonal braces 18 and 19 which are pivotally connected in the middle by means of a pivot pin 20 and have their upper ends secured to the side 80 bars by means of the bolts 21. The shelf is then placed between the side bars and rests upon the cross bars 14. This shelf comprises the upper plate 22 having its corners provided with the cut-out portions so that 85 when the shelf is resting upon the cross bars 14 the key 16 will pass through these cut-out portions. Side strips 23 and 24 are carried by the plate 22 and constitute side 90 flanges between which the bars 25 extend. These bars 25 carry hooks 26 which are preferably formed from wire having its ends 95 twisted together and its intermediate portions spread out to form the double hook as clearly shown in Fig. 6. Plates 27 having hooked ends 28 are secured to the end portion 100 of the bar 24 and have their hooked ends engaging pins 29 carried by the side bars 11 so that the forward portion of the side walls 105 will be braced together, thus prevented from spreading apart. The bracing bars 18 and 19 prevent the rear portions of the side walls from spreading apart so that it is not necessary to provide the hooked plates at the rear corners of the shelf. The cover for the 110 wardrobe is now put in place and rests upon the upper ends of the side bars 10 and 11. This cover comprises the plate 30 carrying the side strips 31 and end strips 32. These side and end strips are secured intermediate 115 their height to the edges of the plate 30 and thus form upper and lower flanges. Inner

side strips 33 and end strips 34 are secured to the lower face of the plate 30 and are positioned in spaced relation to the outer strips 31 and 32, thus forming pockets in which the upper ends of the side bars 10 and 11 fit. The inner strips 33 and 34 are of such depth that when the cover is in place the inner strips will rest upon the upper ends of the key 16, thus giving additional support to the cover. The frame of the wardrobe is now assembled and from inspection of the drawings it will be seen that a frame work has been provided which is easily taken apart and put together, and which is so constructed that a very strong and durable wardrobe will be provided. The curtains 35 are each provided at their upper edges with the rings 36 carrying short bars 37. These bars 37 are mounted in a split tube 38 secured to the cover and extending along the lower edges of the end and side strips 31 and 32 and contacting with the inner side strips 33 and 34. These split tubes are of such length that they will just fit nicely between the side bars 10 and 11, the space between the ends of the tubes and the bars being such that the small bars 37 cannot slip out of the ends of the tubes when the cover is in place, although they may freely slide in the tube. The wardrobe is now ready for use and clothes may be hung upon the hooks 26 while hats and other articles may be placed upon the shelf. It is not necessary to have a curtain at the rear side of the wardrobe since the wardrobe will be placed against the wall, and therefore, it will only be necessary to have curtains at the ends and forward side.

Having thus described the invention what is claimed as new, is:—

1. A wardrobe comprising end walls, each having vertical angle bars, cross bars carried by said angle bars, bracing bars connecting said end walls, a shelf resting upon said cross bars and extending between said end walls, said shelf comprising a plate provided with a cut-out portion in each corner, keys carried by said angle bars and passing through said cut-out portion, side strips carried by said plate and fitting between said end walls, cross strips secured to said plate and secured between said side strips, hooks carried by said side strips and engaging said angle bars to brace said end walls, a cover mounted upon said angle bars, and curtains carried by said cover.

2. A wardrobe comprising end walls, bracing bars connecting said end walls, a shelf carried by said end walls, article suspending hooks carried by said shelf, a cover carried by said end walls, said cover comprising a plate, side and end strips secured to said plate and extending above and below the same, inner side and end strips secured to the lower face of said plate in spaced relation to said first mentioned side and end strips to form pockets in which the upper ends of said end walls fit, curtains for said wardrobe, and means for slidably connecting said curtains with said cover.

In testimony whereof I hereunto affix my signature in presence of two witnesses.

JOHN AXEL KINDBERG.
